(57) **CLAIM**

The ornamental design for a lighting component, as shown.

DESCRIPTION

FIG. 1 is a front, top, right side perspective view of a lighting component showing my new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken lines shown in the drawings illustrate portions of the lighting component that form no part of the claimed design.
